Walter D. Wood Inventor
By his Attorney Chas. C. Walker.

UNITED STATES PATENT OFFICE.

WALTER D. WOOD, OF NEW YORK, N. Y., ASSIGNOR TO FUEL SAVING COMPANY, OF ALLENTOWN, PENNSYLVANIA, A CORPORATION OF PENNSYLVANIA.

COMPENSATED DRAFT-MANOMETER.

1,197,881.

Specification of Letters Patent. Patented Sept. 12, 1916.

Application filed March 23, 1914. Serial No. 826,643.

To all whom it may concern:

Be it known that I, WALTER D. WOOD, a citizen of the United States, residing at Port Richmond, Staten Island, in the borough of 5 Richmond, city and State of New York, have invented certain new and useful Improvements in Compensated Draft-Manometers, of which the following is a specification, reference being had therein to the 10 accompanying drawing.

My present invention relates to a manometer. It differs from and is an improvement over the registering and recording devices which have hitherto been used for the 15 purpose of showing the difference in draft or pressure and rate of combustion throughout steam boilers, furnaces, etc., in that its main object is to enable a complete and instantaneous control to be had of a system for 20 firing powdered coal in locomotives especially, as well as with other engines, in order that there may be complete control at all times of the amount of fuel fed to the firing chamber for the prevention of back 25 fire, smoke and over feeding; this being necessary, as the rate of combustion in a locomotive and the draft which ordinarily controls the same changes so rapidly between 30 maximum or minimum limits, being practically zero when the throttle is closed and maximum when the engine is running with the throttle full open.

The invention is especially adapted for use in conjunction with my improved apparatus for burning fine fuel in the furnaces of locomotives as described and claimed in my co-pending application for Letters Patent filed March 23, 1914, Serial No. 826,641.

The invention, therefore, consists essentially in the construction, arrangement and combination of parts, substantially as will be hereinafter described and then more particularly pointed out in the claims.

The accompanying figure of drawing represents in elevation, with certain parts in section, my improved manometer shown as practically applied to a fine fuel burner arranged on a locomotive and its tender.

Although my present improved manometer is intended for a great variety of different forms of compensated draft apparatus, so that the register may be directly read with ease and convenience, yet I do not

wish to be restricted to any single application of the device. However, in order to afford a complete explanation of a practical way of applying and operating the invention I have in the present embodiment thereof shown the same in connection with a number of mechanical features belonging to the improved apparatus contained in my co-pending application hereinabove referred to, and in said apparatus, as shown in the drawing, it will be seen that 1 designates a fuel tender carrying a supply of pulverized or finely disintegrated fuel; 2 a steam boiler on a locomotive; 3 the firebox of the boiler furnace; 4 the door to said firebox; 5 some suitable flooring in the cab or otherwise for the fireman, engineer, motorman, or other attendant, who has the apparatus under his control. The tender 1 and the locomotive are coupled together in the ordinary way as indicated at 28. On the tender is a centrifugal fan or blower device 6, which discharges into a conduit leading to the firebox 3 and consisting of pipes, 10, 11 and 14; pipes 10 and 11 being united by angular connections 12, and pipes 11 and 14 being united by angular connections 13. The pipe 14 discharges into the interior of a nozzle cylinder 17 of greater diameter, which cylinder discharges into the opening 16 at the bottom of the firebox 3. Thus the pipes 14 and 17 serve as a duplex nozzle for carrying the fine fuel into the firebox. On the tender alongside of the fan 6 is a steam turbine 7 receiving its steam from the boiler 2 through pipe 8, and discharging its exhaust into the locomotive stack through pipe 9. Steam turbine 7 drives the fan 6. Its shaft is suitably geared to shaft 22, by pinion 21 and gear wheel 20, so as to operate a feed device (not shown) within housing 19 which carries the fine fuel forward from its bin into a hopper 23 which discharges at the bottom end into the pipe 10. Air for the purpose of promoting the combustion is supplied to the nozzle cylinder 17 through openings 15 at the sides having shutters 34 which are operated automatically by any suitable lever, as at 35, the details of which are not shown. Air is also admitted into the firebox directly through openings 18 alongside of the cylinder 17, and having shutters 105 operated by a proper system of levers, as at

36. These details, however, form no part of the present application, and are simply given here in brief to describe one form of apparatus with which my improved manometer may be employed.

29 denotes a manometer dial or face on which readings can be had showing the amount of pressure at certain points, also readings showing the corresponding amount 10 of fuel being fed, as I shall explain, and this face is suitably located in the cab or at some other point where the fireman, engineer, or other attendant can easily observe the same, and thus have the entire mechanism 15 completely under control at all times. The air pressure or rather vacuum within the firebox 3 is determined by running a pipe 25 from said box to the manometer dial and allowing it to lead to a U-shaped glass 20 tube 31 arranged in connection with the face 29 and having a series of graduations 1, 2, 3, or otherwise, at 32. The air pressure in the fan 6 and the amount of fuel being fed is determined by leading a pipe 24 from 25 some suitable point in the discharge of the fan by running said pipe to the manometer face 29 where it connects with a U-shaped glass tube 30, one leg of which is provided with a series of graduations 1, 2, 3, or otherwise, 30 at 33, the other being open to the atmosphere. There are thus in the manometer two U-shaped glass tubes, one connected to the fan and the other to the firebox. The pipe 24 connected to the fan conveys air 35 pressure to the tube 30; while through the pipe 25 connected to the firebox there is a drawing or sucking action which has a vacuum producing effect upon the contents of the tube 31. These manometer tubes 30 and 40 31 contain water or some other suitable liquid, as I have indicated in the drawing, and the air pressure on the water column of the tube 30 and the vacuum pull upon the water column in the tube 31, show directly in 45 inches or other graduations on the scales 32 and 33.

The calibration of the manometer must, of course, be determined by experiment, and in some arbitrary way so that there 50 may be a definite correspondence between the graduations in the two tubes, in order to tell properly how much air pressure is needed from the fan to perform a required duty in the firebox to enable the required 55 combustion to take place, and also to show the maximum amount that can be fed without overfeeding. The fireman, by observing the scale 33, will be able to instantly tell how much the air pressure is at the fan 60 outlet and accordingly how much coal is being fed to the fire box and by regulating speed of fan by turning the valve 40 in steam pipe 8 so that more coal will not be fed into the firebox than the draft at the 65 time in the firebox can properly accommo-

date for proper combustion; over-feeding, back firing and smoke are thus prevented; such firebox draft being simultaneously ascertained by an inspection of the scale 32 alongside of the scale 33, said fire box draft 70 being dependent entirely upon the amount of steam being exhausted from the cylinder into the stack (not shown) which communicates with said fire box through flues or fire tubes in the front end of the same 75 and through which the products of combustion reach the outer air. It is, therefore, seen that the draft in the fire box is independent of the rate of combustion. If for instance the fireman desires to increase the 80 fire, and scale 32 shows a draft in firebox of, say, 3, he may speed up the fan until the scale 33 reaches the graduation 3, such being the outside limit at that instant, and not permit any further increase, thus absolutely preventing an excess of coal from being fed to the firebox. Of course, it will be understood that by experiment, I can determine how much the air pressure and consequent fuel feeding shall be for a given 85 draft pressure, and after these arbitrary figures have been determined, and scales 32 and 33 graduated accordingly, it will be easy for the fireman or other attendant to control the air pressure at the two points 90 by observing these scales. This prevents any over-feeding and also makes it impossible for back firing to occur.

I have represented an alternative plan for the determination of the amount of 100 coal which is being fed, which plan consists in the employment of a speedometer in lieu of the pressure gage 33. Such speedometer is shown at 27-connected by a flexible shaft 26 with the conveyer shaft, on which 105 the gear 20 is mounted. The speedometer will be graduated to read in ounces or other quantities corresponding with the graduated scale which indicates the pressure of the firebox draft. As the feeding mechanism 110 operates under the impulse of the actuating devices, the speed of the feed mechanism will be indicated on the speedometer, and the number of pounds of coal dust being fed at any one time can be 115 quickly read, and by proper manipulation of the apparatus, the coal fed will be proportioned to the draft in the firebox.

I do not wish to be restricted to the use 120 of my improved manometer on a locomotive engine, nor to any other particular kind of engine. I have devised and constructed it for the purpose of showing the best results in the operation of a fine fuel burner wherever the latter may be located and for whatever use, and the essential idea of the invention is to enable the attendant to read the pressure in the coal delivery and the combustion chamber and properly relate the same to each other so 125 130

that the best results may be had. Therefore, it will be understood that a great number of changes may be made in the precise structure, location, and arrangement of 5 the various parts, without exceeding the scope of the invention.

Having thus described my invention, what I claim as new and desire to secure by Letters Patent, is:

- 10 1. The combination with a fine fuel burner, including a firing chamber and an air blast device, of an indicating device comprising two indicators, a connection between one indicator and the air blast device so that said indicator may show the 15 pressure of said blast and thereby the rate of combustion of the fuel being fed, and also a connection between the other indicator and the firing chamber, so that the 20 draft vacuum may be indicated, both indicators being coöperatively related so that the pressure in the fuel deliver and the

firing chamber may be easily read and properly related to each other.

2. The combination with an apparatus 25 for feeding and burning powdered fuel, said apparatus including a fluid pressure fuel feeder and a firing chamber, of an indicating device having U-shaped glass tubes, each provided with a scale, a connection between one tube and the fluid pressure feeder, and a connection between the other tube and the firing chamber, said scales on the tubes having a coöperative relation which enables the pressure in the 30 fuel delivery and the firing chamber to be read and related to each other so that the best results in firing may be had.

In testimony whereof I affix my signature in the presence of two witnesses.

WALTER D. WOOD.
